Application July 30, 1940, Serial No. 348,467

6 Claims. (Cl. 99—262)

This invention relates to smoke houses for curing meat products and the like.

One of the objects of this invention is to provide an improved smoke house construction.

Another object of the invention is to provide an improved means for revolving products being cured or smoked during such processing.

Another object of the invention resides in the construction of a smoke house with fixed overhead tracks for sustaining transferable product supporting elements, and means for revolving a plurality of such product supporting elements in said smoke house.

Another object of my invention is to provide an improved mounting for a product supporting element on which product to be smoked or cured may be hung so that the supporting element may be revolved while being supported upon fixed tracks within a smoke house.

Another object of my invention is to provide a smoke house suitable for displaying the process of smoking meat and like products.

It has been suggested that smoke houses be constructed in such a manner as to permit movement of the elements on which the product to be smoke is carried. This type of construction usually takes one of two forms: an endless conveyor traveling throughout the smoke house on which product is hung, or revolving individual smoke trees or cages in which product is hung. My invention relates to the latter type of smoke oven, in which product to be cured is loaded on smoke trees outside of the oven, the smoke trees travel on overhead rails from the point of loading to the smoke oven, and an arrangement whereby the smoke trees are revolved within the oven.

It has been found that movement of the product being smoked results in a more uniform product, apparently due to the fact that movement of the product subjects each piece to the same conditioning atmosphere as other pieces in the smoke house, and thereby prevents some product from being oversmoked while other product adjacent to it is undersmoked.

In the smoke oven disclosed herein, the smoke trees are revolved at a speed of approximately one revolution per minute. The movement of the trees, while slight, does interfere with a direct upward movement of the smoke, causing it to be deflected laterally, and thereby secures uniform treatment for the product contained thereon.

In addition to developing this arrangement for a smoke house which results in an improved

product, I have been able to combine with that arrangement features which permit it to be used for display purposes. I have designed a smoke house in which the operations involved in smoking product can be clearly seen and studied.

The invention will be readily understood by reference to the drawings in which similar reference characters indicate similar parts of the several figures.

10 Figure 1 is a vertical section through my improved smoke house at the vertical plane 1—1 of Figure 5.

Figure 2 is a plan view at the horizontal plane 2—2 of Figure 1.

15 Figure 3 is a cross-sectional view of the smoke pit preferred in connection with the smoke house of the present invention, such as along the vertical plane 3—3 of Figure 2.

Figure 4 is an enlarged view of the air pipes used in connection with the fire pit shown in Figure 3.

20 Figure 5 is a plan view at the horizontal plane 5—5 of Figure 1, showing the layout of the oven and of the trolley rails in the first floor of the oven.

25 Figure 6 is a plan view at the horizontal plane 6—6 of Figure 1, showing the layout of the second floor of the oven and showing a number of smoke trees in place for the smoking operation.

30 Figure 7 is a partial plan view along the horizontal plane 7—7 of Figure 1, showing the layout of the mechanism used for causing the smoke trees in the first floor oven to revolve.

Figure 8 is a plan view along the horizontal plane 8—8 of Figure 1, and shows the layout of the mechanism causing rotation of the smoke trees located in the second story.

35 Figure 9 is an enlarged side view of the preferred mechanism used to rotate the smoke trees.

40 Figure 10 is an enlarged end view of the preferred driving means used to cause the smoke trees to revolve, such as at the vertical plane 10—10 of Figures 5 and 6.

Figure 11 is a side view of the carriage for supporting the rotatable smoke trees.

Figure 12 is a cross-sectional end view of the carriage supporting the rotatable smoke trees.

45 A preferred embodiment of my invention is designed for displaying the smoking of meat products in an exhibition hall or like building 20, as shown in Figure 1, and comprises a plurality of individual two-story smoke houses such as 21, 22, 23, and 24, grouped around an operating alley 25, as more clearly shown in Figures 2 and 5 to 8.

50 Each of the smoke houses is operated independ-

ently but all are grouped to form a unitary structure 26. In such an embodiment of a smoke oven it is desirable that the outer walls be transparent as will be more fully described hereafter.

Still referring to Figure 1, the smoke oven 26 is constructed upon a floor 27 which preferably is slightly lower than the floor 28 of the exhibition hall 20. In view of the fact that the preferred embodiment discloses a smoke oven in which the smoking operations are visible from the outside, the outer wall of the oven is constructed of glass or similar transparent material, and is preferably of polygonal shape. In the preferred embodiment of my invention I employ outer walls of double panes of plate glass, such as 29 and 30, (Figures 5 and 10) separated by an air space 31 and set in frames 32, so that while the walls are transparent they do not conduct heat therethrough. As shown in Figure 5, the glass walls are supported by a plurality of columns 33 constructed of steel or other suitable material. A railing 34 around the smoke oven protects the glass wall from damage by persons watching the operation of the oven.

As indicated in Figure 1 each of the individual smoke ovens and the operating alleys are divided into three floors, the lower of which is the fire pit 35 in which the smoke and generating apparatus of the oven is located. Above the fire pit 35 is the first floor section 36 in which meat or similar products can be hung for smoking. The floor of this section 36 will be approximately, or preferably slightly above the floor 28 of the exhibition building 20, so as to permit persons to view the fire pit, and so that the product which is contained in the first floor section is approximately at eye level. Above the first floor section 36 is a second section or story 37 similar in all respects to the first story or section 36.

Fire pit 35 is separated from the first floor oven 36 by means of steam coils 38 resting upon any such suitable support such as I beams 38a. It is desirable to maintain the temperature uniform throughout the smoke house so that it is advisable to have the steam coils 38 relatively closely spaced throughout the floor area of the smoke oven. Superimposed upon the steam coils 38 is a grating 39 which serves as a floor suitable for use by operators, but which will not interfere materially with the flow of heat, smoke, and air therethrough. Likewise, the first floor of the oven is separated from the second floor thereof by a second steam coil 40 supported on any suitable means, such as I beams 41. Superimposed upon steam coils 40 likewise is grating 42.

Smoke and atmosphere from each smoke oven are exhausted through vents 43 located in the roof 44 of each oven. These vents comprise an exhaust duct 45 opening to the outer atmosphere, equipped with a suitable damper 46 and with a motor driven exhaust fan 47. The exhaust duct can be concealed and braced in any suitable manner from rigid means such as the false smokestack 48.

As best indicated in the plan views and Figure 5 in particular, the preferred embodiment of my invention discloses a plurality of individual smoke ovens, such as 21, 22, 23, and 24, grouped around an operating alley 25. The individual ovens are separated by partitions 49, 50, 51, 52 and 53, constructed of a strong sanitary material such as brick with a tile surface. The arrangement of each of the individual smoke ovens is substantially identical, so that a detailed description of

any of them would illustrate the arrangement of every other oven.

As shown in Figure 2, the floor of fire pit 35 is preferably one that is impervious to moisture such as concrete or brick and slopes gently to a floor drain 54, so that the oven may be periodically washed and the water readily removed therefrom. Access to the fire pit may be gained from the operating alley 25 by means of doorway 55 which may be tightly closed by means of a tight fitting door 56. It will be noted that roughly positioned in the center of the fire pit 35 of each individual smoke oven is located a smoke box 57.

The smoke box is supplied with air from fan 58 which is located in the fire pit operating alley and is driven by motor 59. The fan is connected by means of piping 60 to the smoke box air pipe 61. Preferably a steam nozzle 62 is set in the floor on each side of the smoke box, and connected to steam line 63. Emission of steam therefrom is regulated by a steam valve 64 located in the operating alley 25 and on the steam line. By this means the humidity of the oven, which is very important in smoking meats, can be controlled at all times from a point outside the oven.

Any of the known smoke generators could be used for generating smoke. However, as more clearly shown in Figure 3, I have used as a smoke pit a small smoke box 65 set in the fire pit floor 27. The smoke box 67 is formed by a rectangular wall 66 integral with the floor and with the portion of one side wall removed as at 67. The wall and floor within the box should be lined with fire brick 68, or similar material. Centrally located within smoke box 65 is air pipe 61 containing a plurality of air outlets 69 as shown in detail in Figure 4.

As shown in Figure 5, access to the first floor of each of the individual ovens from operating alley 25 may be secured through doorway 70 which may be tightly closed by door 71. The operating alley 25 likewise opens into meat holding room 72. A trolley rail 73 extends from meat hanging room 72 throughout the length of the operating alley 25, and branches into each of the individual smoke ovens. A preferred arrangement of the trolley rails 73 within the individual smoke ovens is shown in Figure 5, although other arrangements could be used without departing from the spirit of this invention.

Referring to Figure 6, it is seen that the arrangement of the second floor of the smoke oven is similar to that of the first floor: doorway 74 opening into the operating alley 25, being tightly closed by door 75. A trolley rail 76 extends from the meat hanging room 72 through the operating alley and into each of the individual smoke ovens on the second floor level. I prefer that the arrangement of the trolley rails in the second floor be identical with that of the first.

It is, of course, understood that the trolley rails 73 and 76 are affixed to the ceilings of their respective sections as by trolley rail hangers 77, as shown in Figure 10.

Referring to Figure 10, products to be smoked, such as hams 78, may be hung for movement along the fixed trolley rails 73 or 76 to and from the smoke oven, and for suspension within the smoke oven on "smoke trees" or frames 79. The smoke trees 79 may comprise a central vertical bar or tube 80 to which are affixed a plurality of horizontal bars 81 upon which the product can be suspended.

Figures 11 and 12 give the detailed construction of the smoke tree suspension means. The central rod 80 is supported on the trolley rail by means of a carriage 82 comprising a horizontal plate 83 to which are affixed uprights 84 at each end thereof. The upper portion of the uprights 84 are bent over to form an inverted U as at 85 with upright 84 and end 86 forming the sides. Trolley wheels 87 are affixed to an axle 88, the ends of which are journaled in bearings 89 in the upright 84, and bearings 90 of the inverted portion in the end 86 of each upright. A bar 91 connects the upper portions of the two uprights in order to strengthen the carriage.

The base plate 83 of the carriage is provided with bearing blocks, one, such as 92, being located substantially beneath the trolley wheels 87 and approximately midway between the ends of the base plate 83, and the other 93 in spaced relationship thereto. The central rod 80 of the smoke tree is journaled in suitable bearings in the bearing block 92, such as roller bearings 94. A gear 95 is firmly affixed to the central rod 80, as by nut 96, so that rotation of the former will provide rotation for the latter. A collar 97 below the bearing block 92 prevents the central rod from being lifted out of position. A second gear 98 is affixed to axle 99, which is journaled in bearing 100, in bearing block 93. The second gear 98 meshes with the gear 95 affixed to the central rod of the smoke tree. The upper end of the axle 99 is provided with a tongue 101 which meshes with a groove in the driving apparatus hereinafter to be described.

Referring now to Figures 9 and 10, rotation of the smoke trees within each oven is provided by an electric motor 102, suspended from and adjacent to the ceiling 44, in each individual smoke oven. The armature of the motor is connected with reducing gears 103, which in turn drive sprocket wheel 104. Adjacent to the motor 102 and substantially parallel with the axis of its armature is a shaft 105 extending substantially across the smoke oven. The shaft 105 is journaled in bearings 106a affixed to the ceiling in any suitable manner, such as by hangers 106a. A roller chain 108 connects the driving sprocket 104 with a similar sprocket 109 affixed to the shaft 105. One end of the shaft 105 is coupled with a mitre gear box 106 by coupling 107. Preferably the mitre gear box 106 will be located in the smoke oven adjacent to the wall located nearest to the dead end of the trolley rail 76. At predetermined points on the shaft 105 are rigidly secured sprockets 110, such sprockets being located at points on the shaft 105 opposite to the preselected stations for location of the smoke trees 79. Affixed to the trolley rail hangers 77 at the preselected points for hanging the smoke trees 79 are arms 111, in which is journaled a vertical shaft 112. To the upper end of shaft 112 is rigidly secured gear 113 and to the lower end is affixed a slideable collar 114, the lower end of which is provided with a groove 115 that meshes with the tongue 101 on gear 98 of each tree. A compression spring 116 between the collar 114 and one of the arms 111 exert a downward pressure on the collar 114 at all times. A guide rail 117 in spaced relationship to trolley rail 73 or 76 is often desirable to prevent swaying of the smoke trees 79. The gear 113 meshes with the gears, not shown in detail, of a mitre box 118 which is suspended immediately above the trolley rail hanger 77 of rail 76. Sprocket 119 of mitre box 118 is

coupled with the driving sprockets 110 on shaft 105 by means of roller chain 120.

The mitre box 106, by means of gearing not shown, rotates a vertical drive shaft 121. The vertical shaft 121 extends through the grating 42 and steam coils 40 constituting the flooring of the second story of the smoke house, and the ceiling of the first story, and is coupled to a second mitre box 122 below said steam coils. The second mitre box 122 translates the motion from the vertical shaft 121 to the rotation of a horizontal drive shaft 123 which extends substantially across the ceiling of the first floor of the smoke oven. The drive shaft 123 is journaled in suitable bearings 124 suspended from the ceiling of such section of the smoke oven as by hangers 125.

At preselected points along the trolley rail adjacent to the ceiling of the first floor of the smoke oven, the trolley rail hangers are provided with the driving arrangement described in detail in connection with the second story, which briefly comprises the arms 111 integral with the trolley hanger 77, a vertical shaft 112 journaled therein, to the lower end of which is affixed slideable collar 114 provided with groove 115. A mitre box 118 is affixed to the ceiling and as closely as may be convenient to the vertical shaft 116. Sprockets 110 on the drive shaft 123 drive sprockets 119 on mitre box 118 by means of chain 120.

In some instances, as disclosed in the lower section of Figure 10, the construction of the smoke oven ceiling prevents the location of the mitre box 118 immediately adjacent to a gear 113 on vertical shaft 112, so that the driving gear of mitre box 118 can not mesh therewith. In such instances the mitre box 118 is provided with a driving sprocket 126 and the gear 113 on shaft 112 is replaced by a sprocket 127, and the two connected by a roller chain 128.

Preferably adjacent smoke trees will rotate in opposite directions. This rotation is easily secured by anyone familiar with mechanics. The revolving of adjacent smoke trees in opposite directions creates a better dispersion of the smoke and conditioning atmosphere of the oven, resulting in a more uniform product.

By means of the gearing shown herein, the smoke trees in each smoke oven are revolved at a predetermined speed from a single motor.

In the operation of the oven the product to be smoked, such as hams 78, are loaded onto the smoke tree 79 in the meat hanging room 72. The required number of smoke trees 79 are then pushed into the smoke oven by hand along the overhead trolley rails 73 and 76, one being placed at each of the preselected points. The slideable collar 114 is raised by the operator and then permitted to drop on the tongue 101 affixed to gear 98 of the smoke tree. The smoke tree is thereby engaged with the driving apparatus of the whole smoke oven. After all the smoke trees have been properly placed and engaged with the driving apparatus, the operator may close the door and start the motor 102. Motion of the motor armature is transmitted to all of the revolvable collars 114 in that smoke oven by the gearing shown in Figures 9 and 10 and fully described above. If the collar 114 has been meshed with tongue 101 of the smoke tree, the tree in turn will revolve; as indicated above, this rotation may be relatively slow as, for example, one revolution per minute. However, this rotation is sufficient to cause sufficient dispersion of the normally vertical cur-

rents of conditioning atmosphere from the smoke pit, to cause uniform treatment of all product in the oven.

It has also been discovered that very good results are secured if only a portion of the smoke trees rotate. In the embodiment shown in the drawings, it will be noted that only the outside trees are rotated, those on the inner rail remaining stationary. The rotation of only a portion of the trees may not create as great a dispersion of conditioning atmosphere as when all revolve, but very satisfactory results can be secured by such means. In the drawings, therefore, the trees on the outer rail are shown connected with the driving apparatus and those on the inner rail are not. However, it is to be understood that to connect all trees to the driving apparatus would be included within the scope of this invention.

The means of revolving the smoke trees disclosed in the present invention is particularly adaptable to display ovens, and discloses a method whereby movable trees can be easily connected with the driving equipment used to revolve smoke trees.

While I have herein described and upon the drawings shown illustrative embodiments of the invention, it is to be understood that the invention is not limited thereto but may comprehend other constructions, arrangements of parts, details, features and method steps without departing from the spirit of the invention.

I claim:

1. A smoke oven including heating and smoking means, said oven having a plurality of individual smoking rooms, each of said rooms being disposed about a common point as a center, a door to each of said rooms, a common alley leading to said center for servicing each of said rooms, said doors all opening onto said alley whereby meats to be smoked may be moved into each of said rooms from said alley.

2. A smoke oven for display purposes including heating and smoking means and having a transparent wall to permit visual inspection of the smoking process, said oven having a plurality of individual smoking rooms disposed in substantially circular arrangement, said transparent wall being disposed around the periphery of said circle, a door to each of said rooms, a common alley for servicing each of said rooms, said doors all opening onto said alley whereby meats to be smoked may be moved into each of said rooms from said alley.

3. A smoke oven for display purposes including heating and smoking means and having a transparent wall to permit visual inspection of the smoking process, said oven having a plurality

of individual smoking rooms disposed in substantially circular arrangement, said transparent wall forming roughly the periphery of said circle, each of said rooms being divided by a horizontal partition to provide different levels for smoking meats, a pair of doors to each of said rooms, one of said doors being disposed at each level, a pair of alleys for servicing each of said rooms at each of said levels, said doors all opening onto said alleys whereby meats to be smoked may be moved into each of said rooms at each level from the corresponding alley.

4. In a smoke oven for smoking a plurality of trees of meats, rotatable trees for holding said meats, means to rotate said trees, said last named means being effective to cause adjacent trees to rotate in opposite directions, said trees being disposed closely adjacent each other whereby the smoky atmosphere surrounding said trees is agitated by the motion of said trees.

5. A smoke oven for display purposes including heating and smoking means and having a transparent wall to permit visual inspection of the smoking process, said oven having a plurality of individual smoking rooms disposed in substantially circular arrangement, said transparent wall being disposed around the periphery of said circle, each of said rooms being large enough to receive a plurality of trees of meats to be smoked, rotatable trees for holding said meats, means to rotate said trees, said last named means being effective to cause adjacent trees to rotate in opposite directions, said trees being disposed closely adjacent each other whereby the smoky atmosphere surrounding said trees is agitated by the motion of said trees, and an opening disposed in the rear wall in each of said rooms whereby said trees may be placed in said rooms.

40 6. A smoke oven for display purposes including heating and smoking means and having a transparent wall to permit visual inspection of the smoking process, said oven having a plurality of individual smoking rooms disposed in substantially circular arrangement, said transparent wall being disposed around the periphery of said circle, said rooms being divided horizontally to provide different levels for smoking meats, rotatable trees for holding said meats, means for supporting said trees at each of said levels, means to rotate said trees, said last named means being effective to cause adjacent trees to rotate in opposite directions, said trees being disposed closely adjacent each other whereby the smoky atmosphere surrounding said trees is agitated by the motion of said trees, and openings in the wall of said rooms whereby said trees may be moved into each level of said room.

EDWARD A. SCHIEWE.
